UNITED STATES PATENT OFFICE.

JOHN W. VAN DYKE, OF BROOKLYN, NEW YORK.

STEAM-GENERATOR.

SPECIFICATION forming part of Letters Patent No. 289,182, dated November 27, 1883.

Application filed March 5, 1883. (No model.)

To all whom it may concern:

Be it known that I, JOHN W. VAN DYKE, of Brooklyn, in the county of Kings and State of New York, have invented certain Improvements in Steam-Generators, of which the following is a specification.

This invention relates to that class of "tubular boilers," so called, in which the water-tubes are placed at an angle to the horizontal, but sloping alternately in opposite directions, thereby forming vertical series of horizontal zigzag tubes joined at their ends by suitable headers or connections.

The object of this invention is to provide a steam-generator of the class mentioned in which provision shall be made for the adequate circulation of the water, for the construction and support of the generator itself independent of supporting-walls, and for the maintenance of the tubes in the requisite position without interfering with the passage of the hot products of combustion of the furnace from end to end of the apparatus.

A further object of the invention is to provide for maintaining the tightness of the horizontal flame-deflecting partitions, which direct the hot products of combustion from the furnace into the requisite relation and contact with the tubes.

My said invention comprises certain novel combinations of parts whereby said objects are secured.

Figure 1 is a longitudinal sectional view of a steam-boiler made according to my said invention. Fig. 2 is a front view and partial vertical transverse section of the same. Fig. 3 is a rear view and partial vertical transverse section of the same, and Fig. 4 is a transverse view of one of the supporting-links.

A is the usual fire-box, and B the posterior space to which the gaseous products of combustion pass immediately as they leave the fire-box A.

C and D are boiler-tubes, the tubes C sloping in one direction, while those D slope in an opposite direction, the ends of the tubes being joined by headers E, so that the tubes constitute zigzag series, of which any desired number are placed side by side, the ends of the series being connected by the headers E, as just explained. The headers E are com-

posed of hollow castings, the outer sides of which are provided with removable plates a, by which, on occasion, access may be had to their interiors. The inner sides of said headers E are provided with circular openings, as at b, into which the adjacent ends of the tubes C and D are inserted, as represented in Fig. 1, and tightened by any suitable means. The headers E at the front of the boiler have their shoulders or projections c raised upon similar projections or shoulders, d, provided at the inner sides of vertical columns F, which latter rest upon any suitable foundation. The headers E at the front of the boiler are therefore suspended upon the columns F.

G is a hollow casting, answering in part to one of the headers E, insomuch as it receives the extremity of the uppermost series of tubes, as represented in Figs. 1 and 2. This casting has an upwardly-projecting neck, e, which passes through a correspondingly-shaped opening in the adjacent portion of the bottom of the steam-drum H, there being of course a tight joint made around the said neck and between the same and the edges of the opening. This neck e constitutes the inlet from the uppermost series of tubes to the interior of the steam-drum H, and is extended upward within the said steam-drum to a height sufficient to prevent the volume of water in the latter from tending to regurgitate backward and downward through the uppermost series of the tubes. When desired, the casting G may be formed without the neck e, and made to simply communicate with the bottom of the steam-drum H, in which case, however, a transverse partition is provided within the steam-drum and extended upward to a degree corresponding to that hereinbefore described with reference to the said neck e, the office of said partition being the same as that of the neck e—namely, to prevent the reflow of the volume of water contained in the main portion of the steam-drum downward or backward through the tubes. The headers E at the rear of the boiler rest upon shoulders or projections f, provided on the adjacent inner sides of vertical tubular pillars I, the lower ends of which are enlarged, as shown at g, and which rest upon any suitable foundation. The headers at the rear of the apparatus are therefore separately and independently suspended upon

the tubular pillars I in very much the same manner that the headers at the front of the boiler are suspended on the columns F. The rearmost ends of the lowermost series of tubes 5 communicate with a horizontal tubular casting, K, the ends of which are bolted or otherwise secured to the adjacent inner sides of the tubular pillars I, and which, by suitable openings provided in the said ends, and also 10 in the adjacent sides of said tubular pillars I, communicate with the interior of the latter. The localities of communication between the casting K and the tubular pillars I are above the enlarged lower portions, g, of the said pillars. Said portions g constitute drums, which 15 may be furnished with suitable blow-off cocks, h.

Extending across from the top of one of the tubular pillars I to that of the other is a hollow casting, L, the interior of which communicates with the interiors of the said pillars, as shown at m, and also with the interior of the rearmost end of the steam-drum H, as shown at n, so that the water, as indicated by 20 25 the arrows in Fig. 1, may circulate alternately from one to the other of the tubes C D through the headers E, thence through the casting G into the front of the steam-drum, thence downward from the rear of the latter through the casting L, through the tubular pillars I, and thence through the casting K to the lowermost 30 35 of the tubes, and so on continuously. The feed-water is introduced to the casting L, so that it mingles with the water the least heated as the same descends from the rearmost end of the steam-drum, and becomes intermingled therewith to such an extent that the volume of water is of substantially uniform temperature by the time it reaches the lowermost of 40 45 the tubes, thereby reducing to a minimum any liability of expansion or contraction from changes of temperature in the generator.

Provided near each end of the casting L—that is to say, in the passages from said casting L to the tubular pillars I—are valves N, arranged to swing outward and to shut inward, so that while the said valves open to permit the circulation of the water in the directions hereinbefore explained, they close in 50 55 case, for any reason, the direction of the circulation of the water is changed. In other words, these valves operate to prevent the backing up of the water, which in practice is frequently experienced in steam-boilers of the class to which my invention relates. It is obvious that the same results will be obtained if the position of the valves N is shifted from 60 65 their location in the casting L to the interior of the tubular pillars I; or, in fact, the said valves are located at any place between the passage n and the ends of the lower series of tubes. In like manner the position of the feed-inlets m may be changed to any desired position between the passage n and the lowermost of the tubes; but the admixture of the feed-water with the least-heated water from the steam-drum H will approximate comple-

tion in proportion as the inlet of the feed is adjacent to the passage n.

It will be observed that the tubular pillars I constitute a vertical water-chamber independent of the connection between the series of tubes through their headers, which said vertical water-chamber affords a means whereby the relatively cold feed-water may be mingled with the least heated of the water circulating through the boiler, and thereby constitute a heating portion of the boiler, which prevents strain from expansion and contraction upon other portions of the boiler. The casting L should be provided with man-holes, covered with suitable man-hole plates, r, in order that, on occasion, access may be had to the valves N, to the feed-inlets, &c.

In order that the flame and hot gaseous products of combustion from the fire-box A may be directed into the most advantageous relation and contact with the tubes C and D—as, for example, as indicated by the curved arrows in Fig. 1—there is provided substantially horizontally between the tubes fire-proof partitions R and S, the lowermost of which extends from the front nearly but not quite to the rear of the apparatus, while the uppermost extends from the back nearly but not quite to the front. This arrangement, however, may be modified according to the size of the boiler, and according as it is desired to allow the hot gaseous products of combustion to escape from an uptake at the front or at the rear. These partitions are 90 95 composed, preferably, of light fire-proof tiles laid directly upon the tubes C and D. By this means the construction is greatly simplified and a better heating effect obtained, for by placing the tiles or flame-deflecting partitions directly upon the tubes separate supports therefor are thereby dispensed with, while the heat absorbed by the tiles from the flames or gases is afterward given out by direct conduction and close radiation to the tubes with which they directly contact, the transmission or diffusion of heat being thus obviously more effective than if the tiles were separated from the tubes. These tiles have their upper edges beveled, as shown at c' in Fig. 1, so that at the intersection of the tiles triangular grooves are formed. These grooves are filled with fire-clay or any suitable cementing material, which, from its position exposed to great heat, will harden. The fire-clay or cement constitutes a 100 105 wedge-like filling, which, in the event of the shrinkage of the tiles or of the shrinking of the cement itself, drops down to the bottom of the wedge-like grooves a', and thereby tends to keep the same substantially tight or closed, 110 115 and thus maintains the integrity of the partition. 120 125

The horizontal spaces between the headers at the two ends of the apparatus are filled in with bricks, as indicated in the drawings. Formed in this brick-work may be openings T, which, in the normal use of the boiler, may be closed by suitable plates, but which, when unclosed, afford access to the tubes C and D,

the partitions R and S, &c., for inspection, cleaning, repairing, and the like. Each of the tubes C or D, as the case may be, is suspended by links V, which may be either, as represented in Fig. 4, composed of duplicate rings cast in one with each other, or of simply oblong links, so that by this means the central portions of the tubes of the generator are connected, the one suspended from the other, and the one enabled by its strength to assist the strength of the others. When desired, a strap (not shown) may connect the uppermost of the links V with the steam-drum H, which latter, from its cylindrical form, is enabled to support without detriment a material portion of its weight on the central portion of the tubes.

I am aware of Patent No. 136,453, and make no claim to the construction shown therein, as I deem it essentially different from my invention.

20 What I claim as my invention is—

1. The combination, in a boiler of the described class, with the steam-drum H and an oppositely-inclined series of pipes, C D, discharging into said drum, of the hollow supporting-pillars I I, connecting at the top with said drum, and the transverse header K, connected at each end with and supported by said pillars at or near the base thereof, and from which the initial end of said series of oppositely-inclined tubes issues, substantially as and for the purpose set forth.

2. The combination, with the steam-drum H, the casting L, and tubular supporting-pillars I, connecting with said casting, of the oppositely-inclined tubes C D, arranged as shown, and their headers E, arranged between and supported by said pillars.

3. The combination, with the steam-drum H

and casting L, of the water-pillars I I, connecting with said casting and supporting the front 40 of the drum, and the columns F, supporting the rear of the drum, with the oppositely-inclined pipes C D and their headers E, arranged between and supported by said pillars and columns, substantially as herein shown and 45 described.

4. The combination of the oppositely-inclined tubes C and D, suitably connected at their ends, the steam-drum H, tubular pillars I, casting L, forming a direct connection between the top of the pillars and the drum, and valves N, the parts being constructed and arranged in relation with each other substantially as and for the purpose herein set forth.

5. The combination, with the tubes C and D, 55 suitably connected at their ends, of the system of links V, arranged upon the said tubes to connect and mutually support the same, substantially as and for the purpose herein set forth.

6. The combination, with the tubes C and D, 60 suitably connected at their ends, of substantially horizontal flame-deflecting partitions composed of tiles or plates of heat-resisting material, having their upper edges beveled and laid edge to edge directly upon and supported by the said tubes, and the grooves thus formed by the adjacent beveled edges filled with cement, fire-clay, or the like, forming wedge-shaped fillings, substantially as and for 65 the purpose set forth.
